UNITED STATES PATENT OFFICE.

GEORGE F. REED, OF PITCAIRN, PENNSYLVANIA.

LOCK.

1,000,946.

Specification of Letters Patent. Patented Aug. 15, 1911.

Application filed May 20, 1909, Serial No. 497,362. Renewed April 21, 1911. Serial No. 622,582.

To all whom it may concern:

Be it known that I, GEORGE F. REED, a citizen of the United States of America, residing at Pitcairn, in the county of Allegheny and State of Pennsylvania, have invented certain new and useful Improvements in Locks, of which the following is a specification, reference being had therein to the accompanying drawing.

10 This invention relates to locks, more particularly strap locks and aims to provide in a manner as hereinafter set forth a lock, which is especially adapted for locking portions of a strap or flexible member together 15 for maintaining the mouth of a receptacle or pouch closed.

Primarily the invention is designed for use for locking the straps of mail pouches for maintaining the latter closed, yet it is 20 to be understood that the lock can be used for any purposes wherein it is found applicable.

Further objects of the invention are to provide a lock for the purpose set forth 25 which shall be simple in its construction, strong, durable, efficient in its use, readily set up in operative position, one that will reduce to a minimum its opening by unscrupulous persons, and inexpensive to 30 manufacture.

With the foregoing and other objects in view, the invention consists of the novel construction, combination and arrangement of parts hereinafter more specifically described and illustrated in the accompanying drawings, wherein is shown the preferred embodiment of the invention, but it is to be understood that changes, variations and modifications can be resorted to which 40 come within the scope of the claims hereunto appended.

In the drawings wherein like reference characters denote corresponding parts throughout the several views; Figure 1 is a 45 view illustrating a lock in accordance with this invention connecting portions of a strap together, the strap being broken away at one end. Fig. 2 is an inverted plan view of the lock casing, with the bottom 50 plate and intermediate plate removed, illustrating the tumblers and the bolt secured to the tumblers whereby portions of a strap are connected together, the strap being broken away at each side of the casing. 55 Fig. 3 is a longitudinal view of a lock in accordance with this invention, the strap

being broken away at each side of the casing. Fig. 4 is a side elevation of a key used in connection with the lock. Fig. 5 is a perspective view, broken away at the center, of the strap. Fig. 6 is a perspective view of the intermediate partition plate. Fig. 7 is a top plan view of a modified form of bolt showing the same connected to a strap, the strap being broken away at each end, and, Fig. 8 is a side elevation of the form of bolt shown in Fig. 7.

A lock in accordance with this invention as hereinbefore stated is particularly adapted for connecting portions of the strap of a mail pouch together so as to retain the mouth of the pouch closed, the strap as is well known extending through a series of loops or eyes on the periphery of the pouch at the mouth end thereof. The lock in accordance with this invention has its casing with its tumblers secured to one end of the strap and its bolt attached to the strap at a point intermediate the end of the latter, the bolt is adapted to be inserted in the lock casing whereby the strap is connected together and when the strap is connected together a portion thereof extends through the lock casing as clearly shown in Fig. 1.

It is obvious that in lieu of employing the strap that a cable or any other suitable flexible member can be utilized. It is also obvious that although the lock is designed primarily for use in connection with the strap at the mouth end of a mail pouch, yet it can be used for locking other receptacles wherein found applicable.

Referring to the drawings in detail 1 denotes the body portion of the strap and 2 and 3 the ends thereof, the ends being enlarged or of greater width than the body portion 1. Although the strap is shown as having two enlarged ends, yet it can be of the same width throughout, or one of the ends can be enlarged and the other end of the same width as the body portion. By providing the two enlarged ends it will prevent the free end of the strap accidentally disconnecting from the lock casing as will be evident when the manner of setting up the strap with respect to the lock casing is considered and which will be presently referred to.

The lock casing is referred to generally by the reference character 4 and comprises 110 side walls 5 and 6, an end wall 7, an intermediate partition plate 8 and a removable

bottom 9. Each of the side walls 5 and 6 is provided with a laterally extending flange 10 having a plurality of openings 11 through which are adapted to extend hold fast devices for connecting the bottom plate 9 to the flanges 10 and also for securing the enlarged end 3 of the strap to the casing. The end wall 7 is of less height than the side walls 5 and 6. The partition plate 8 is positioned 10 within the casing 4 so that it will be flush with the lower edge of the end wall 7 whereby a passage 12 will be provided between the end 7, said plate 8 and the bottom plate 9 and through said passage 12 is drawn the 15 body portion 1 of the strap. The partition plate 8 is formed at one end with a V-shaped notch 13 providing a clearance for the operation of the bolt of the lock and at its other end with an opening 14 which registers with a recess formed in a lug 15 integral with the top wall 16 of the casing 4. Extending through the opening 14 and engaging in the recess lug 15 is a screw 17 for securing the partition plate 8 in position. The 20 upper face of the partition plate approximately centrally thereof has connected thereto a vertically extending pin 18 having its lower portion surrounded by a boss 19, which constitutes a centering device for the key 20, the said boss 19 being of such diameter as to extend in the cut-away portions 21 forming recesses in the bit 38. The shank of the key is hollow to receive the pin 18, the diameter of the shank being such as 25 to pass within the boss 19 and so that the boss 19 can enter the recess 21. The pin 18 is of such height as to extend within the key opening 22 formed in the top plate 16. That end of the casing 4 which is opposite 30 the end wall 7 is open to allow entrance of the bolt and the top plate 16 at the open end of the casing 4 has depending from its lower face a pair of guide lugs 23 for the reception of the shank of the bolt to be presently 35 referred to. The lugs 23 form a guide passage for the shank of the bolt when the latter is inserted in the casing 4.

Arranged within the casing 4 are a pair of tumblers 24 and 25 each pivoted at one end, 40 as at 26, and when in normal position abutting against each other at the pivoted ends as at 27. Each of the tumblers intermediate its ends is formed with a curved bearing surface 28 and against the bearing surfaces 45 28 the curved arm 29 of U-shaped spring 30 engage for normally maintaining the tumblers in abutting engagement or in other words permanently tending to shift one tumbler toward the other. The U-shaped 50 spring 30 seated within the casing 4, is of less height than the end wall 7, engages the said wall 7 and also the side walls 5 and 6. The tumblers 24 and 25 on the inner faces 55 thereof near the free end of each is cut away 60 to provide a shoulder 31 and the said shoul-

ders 31 being adapted to engage the head of the bolt of the lock for connecting it to the tumblers. Interposed between the tumblers 24 and 25 is a stop lug 32, the function of which is to arrest the inward 70 movement of the bolt during the locking operation.

The bolt of the lock consists of a carrier 33, which is positioned against the upper face of the body portion 1 of the strap, and is provided with an angularly disposed end 34 which constitutes an end wall for the open end of the casing 4 when the bolt is in engagement with the tumblers 24 and 25 as clearly shown in Figs. 2 and 3. The carrier 33 has formed integral therewith a shank 35 through which extends the rivets 36 for connecting the bolt to the body portion 1 of the strap. The shank 35 is of a width as to extend between the lugs 23 when the bolt is inserted in the casing 4 so as to engage the tumblers 24 and 25. The shank 35 of the bolt terminates in a spear-shaped head 37 which when the bolt is inserted in the lock casing 4 is adapted to force the tumblers 24 and 25 apart, until the said head 37 clears the shoulders 31, which will then allow of the tumblers 24 and 25 to be moved toward each other through the medium of the spring 30, the shoulders 31 then positioning themselves at the rear of the spear-shaped head 37 whereby the bolt is retained within the lock casing and maintained in such position until the tumblers are separated by the bit 38 of the key. To 100 facilitate the separations of the bolt from the casing 4 when the tumblers 24 and 25 are moved away from each other through the medium of the key, the body portion 1 of the strap has suitably connected thereto a flat spring 39, (see Fig. 1). The spring 39 is under a state of tension when the bolt is connected by the tumblers to the casing, so that when the tumblers 24 and 25 are shifted clear of the spear-shaped head 37 105 of the bolt, the spring 39 will distend and force the bolt from the casing.

When positioning the lock with respect to the strap, it will be stated that if a strap is employed having the enlarged end as indicated by the reference characters 2 and 3, before the bottom plate 9 is secured to the flanges of the side walls 5 and 6 and also to the end 3 of the strap, the casing is mounted upon the body portion 1 of the strap at one side of the large or free end 2. The bottom plate 9 is then secured to the enlarged end 3 and to the flanges of the side walls 5 and 6. If the free end of the strap is not enlarged the lock casing is secured directly to the enlarged end 3 or to the strap and the free end of the strap passed through the passage 12. The bolt is then secured at a proper point to the strap depending on what would be the diameter of the mouth of 120 125 130

the pouch so that when the strap is connected together the diameter of the connected portion of the strap will be such as to not allow the mouth of the sack to be opened or rather hold the mouth of the sack tightly closed.

In Figs. 7 and 8 a modified construction of bolt is illustrated, the bolt being so designed that the strap can slip through the bolt in one direction but not in the opposite direction, thus provision is made for decreasing the diameter of the connected portion of the strap in case of the mouth of the pouch not being securely closed. The bolt 10 as shown in Figs. 7 and 8 comprises a body portion 39 having an angular shaped end 40 which constitutes one end wall of the lock casing 4 and is further provided with an angularly disposed keeper 41 for coupling the bolt to the body portion 1 of the strap. The bolt further comprises a shank 42 which when the bolt is inserted in the casing 4 extends between the lugs 23. The shank 42 terminates in a spear-shaped head adapted to be engaged by the shoulders 31 of the tumblers so as to secure the bolt in locking position. The shank 42 is provided with a recess 44 which also extends through the body portion or carrier 39. The recess is formed with inclined walls 45 and 46. Arranged within the recess 44 is an inclined arm 46 pivoted at its upper end as at 47 and at its other end terminating in a transversely extending inclined clamping bar 48 which engages the upper face of the body portion of the strap 1. The clamping bar 48 is maintained in engagement with the body portion of the strap by a spring 49 which abuts against one of the walls of the recess 44 and also against the bar 48. By setting up the bar 48 in the manner stated, the strap 1 can be pulled forwardly through the keeper 41, but in case attempt is made to pull the strap rearwardly, the movement of the strap will be resisted by the clamping bar 48, as is evident. By this construction provision is made for decreasing the diameter of the connected portion of the strap or rather the loop formed by the connected portion of the strap so as to tightly close the mouth of the pouch when occasion so requires.

By providing the partition plate 8 with the boss 19 the operation of the tumblers to release the bolt cannot be effected unless the strap 1 can be pulled forwardly to receive the pin 18 and the bit 38 so recessed as to receive the boss 19, therefore the lock is provided with means to prevent it being opened unless one possesses a key of the necessary construction.

What I claim is:-

1. In combination, a lock casing adapted to be secured to a strap and provided with a plurality of tumblers and further pro-

vided with a passage through which is adapted to extend a portion of the strap, and a bolt adapted to be attached to another portion of the strap and further adapted to engage the tumblers when the strap is pulled through said passage whereby the bolt is coupled with the casing and portions of the strap connected together to form a loop for closing the mouth of a receptacle. 70

2. In combination, a lock casing adapted to be secured to a strap and provided with a plurality of tumblers and further provided with a passage through which is adapted to extend a portion of the strap, a bolt adapted to be attached to another portion 80 of the strap and further adapted to engage between the tumblers when the strap is pulled through said passage whereby the bolt is coupled with the casing and portions of the strap connected together to form a 85 loop for closing the mouth of a receptacle, and a shiftable clamping bar adapted to engage the strap when the bolt is engaged by the tumblers to prevent the increasing of the diameter of the loops when the strap is pulled in one direction and free of the strap when the latter is pulled in the opposite direction whereby the diameter of the loop can be decreased when the bolt is engaged by the tumblers. 95

3. In combination, a lock casing adapted to be secured to a strap and provided with a plurality of tumblers and further provided with a passage through which is adapted to extend a portion of the strap, a bolt adapted to be attached to another portion of the strap and further adapted to engage the tumblers when the strap is pulled through said passage whereby the bolt is coupled with the casing and portions of the 100 strap connected together to form a loop for closing the mouth of a receptacle, and a spring engaging the strap for automatically projecting the bolt from the casing when the bolt is released from the tumblers. 105

4. In combination, a lock casing adapted to be secured to a strap and provided with a plurality of tumblers and further provided with a passage through which is adapted to extend a portion of the strap, a bolt adapted to be attached to another portion of the strap and further adapted to engage the tumblers when the strap is pulled through said passage whereby the bolt is coupled with the casing and portions of the 115 strap connected together to form a loop for closing the mouth of a receptacle, and a shiftable clamping bar adapted to engage the strap when the bolt is engaged by the tumblers to prevent the increasing of the diameter of the loops when the strap is pulled in one direction and free of the strap when the latter is pulled in the opposite direction whereby the diameter of the loop can be decreased when the bolt is engaged. 120

125

ing the open end of the casing, said casing provided with guide lugs for the bolt.

11. In combination, a lock casing provided with a plurality of spring controlled 5 tumblers and further provided with a longitudinally extending passage open at each end and of a length equal to the length of the casing, said casing having an open end, a partition plate within said casing and 10 forming one wall of said passage, a bolt provided with a carrier and adapted to extend in said casing at the open end thereof and engaging said tumblers whereby the bolt is coupled with the casing, said carrier 15 constituting a means for closing the open end of the casing, and means on said partition plate for centering the key.

12. In combination, a lock casing provided with a plurality of spring controlled 20 tumblers and further provided with a longitudinally extending passage open at each end and of a length equal to the length of the casing, said casing having an open end, a partition plate within said casing and 25 forming one wall of said passage, and a bolt provided with a carrier and adapted to extend in said casing at the open end thereof and engaging said tumblers whereby the bolt is coupled with the casing, said 30 carrier constituting a means for closing the open end of the casing, guide lugs within the casing for the bolt, said partition plate cut

away to provide a clearance for the entrance of the bolt and means upon the partition plate for centering a key.

13. In combination, a lock casing adapted 35 to be secured to a strap having one end open and provided with a plurality of tumblers and further provided with a longitudinally extending passage through which is adapted 40 to extend a portion of the strap, a carrier mounted on the strap and having an angular end, a bolt upon the carrier and adapted 45 to extend through the open end of said casing and engage the tumblers when the strap is pulled through said passage whereby the bolt is coupled with the casing and portions of the strap connected together to form a loop for closing the mouth of a receptacle, said angular end of said carrier 50 constituting means for closing the open end of the casing when the lock is in engagement with the tumblers, and a partition plate mounted in said casing and constituting one wall of said passage and having one 55 end cut-away to provide a clearance for the entrance of the bolt in the open end of the casing.

In testimony whereof I affix my signature in the presence of two witnesses.

GEORGE F. REED.
